APPARATUS FOR ADJUSTING AND STOPPING THE PRINTING IN AUTOMATIC PLATEN PRINTING PRESSES

Artur Büttner, Heidelberg, Germany, assignor to Schnellpressenfabrik Aktiengesellschaft Heidelberg, Heidelberg, Germany

Application May 22, 1933, Serial No. 672,313
In Germany June 4, 1932

6 Claims. (Cl. 101—306)

This invention relates to apparatus for adjusting and stopping the printing in automatic platen printing presses of the kind in which the platen is actuated by means of a toggle mechanism.

In platen printing presses of the kind referred to, it has been proposed for the purpose of starting and stopping the printing, to construct the pivot of the toggle mechanism by means of which the latter is connected to the frame of the press in the form of a rotatable eccentric, by the rotation of which the pivot is displaced and the extent of the rocking movement of the platen is varied to suit varying thicknesses of paper or material to be printed on or the depth of impression to be made, by which means also the printing can be started and stopped by sufficient displacement of the pivot by rotation of the eccentric. In this arrangement, the entire operating pressure acts on the eccentric so that regulating of the impression pressure can only be effected in those positions of the toggle mechanism in which the latter is relieved of the impression pressure. In the case of very high working speeds, it is therefore very difficult to obtain exact adjustments of the impression.

The present invention has for its object to overcome these drawbacks and with this object in view the invention consists substantially in this that the stationary pivot of the toggle mechanism is displaceable in a straight line by means of a screw threaded adjusting member (worm or the like). This screw threaded member, which is preferably in the form of an irreversible worm, relieves the adjusting means from the considerable compression forces so that adjustment of the toggle mechanism is possible even during the actual printing operation without the expenditure of a large amount of force and it is consequently easy to effect fine adjustment by displacing the fulcrum pivot of the toggle mechanism. The screw threaded adjusting member can be turned inside a nut by means of a pivotally mounted hand lever arranged at the front side of the printing press. In order to obtain very exact adjustment of the impression pressure and enable the hand lever to be secured in the adjusted position, the hand lever may be connected to a locking member guided so as to travel in a straight line, which locking member may be displaced by means of a screw spindle.

The straight line displacement of the stationary pivot of the toggle mechanism enables a shear piece to be interposed between the worm or the like and the bearing of the toggle mech-

anism so that in the case of excessive pressure in the bearing of the toggle mechanism, the shear member is ruptured and the press can continue to run without danger.

The apparatus according to the invention is illustrated on one form of construction by way of example in the accompanying drawings, in which:

Figure 1 shows a side view of a platen press equipped with the device according to the invention;

Figure 2 shows a part of the device in longitudinal section on a larger scale; and

Figure 3 shows a partial front view of the platen press according to Figure 1, likewise on the larger scale.

Fig. 4 is a vertical section taken on line 1—1 of Fig. 3.

In the pedestal 1 of the press, which carries a frame 2 for the reception of the printing bed, 20 the platen 3 swings about a pivot 4. The driving of the platen 3 is effected from the main shaft 5, upon which a crank 6 is secured. To the latter is attached a connecting rod 7, the other end of which is connected with the central joint pin 25 8 of a toggle lever 9, 10. The arm 9 of this toggle lever is pivoted to the lower end of the platen 3, and the arm 10 is connected by a pivot 11 with a displaceable bearing 12. On the platen 3 are rotatably arranged grippers or fingers 13, 30 which receive sheets to be printed from a feeding pile located upon a table 14, and convey them, after the printing, on to a delivery pile, likewise arranged upon the table 14.

The stoppage of printing and the regulating of the pressure are effected by displacing the bearing 12. For this purpose the bearing 12 is provided with a sliding pin or stem 15 (Figure 2), which is displaceable in a bush 16 fixed in the base 1, and terminates in a journal 17. Upon 40 the latter is rotatable a worm or screw-threaded sleeve 18, which bears at one end against a shear ring 19 and at the other end against an abutment ring 20. The bush 16 is provided with a corresponding internal screw thread, in which 45 the screw 18, as it rotates, can move to the left or right, as a result of which the toggle-lever bearing 12 is displaced in one direction or the other. With the screw 18 is connected fast a lever 21, which engages, as shown in Figures 2 50 and 3, by means of a lateral tappet 22, in a notch in a toothed segment 23, which is freely rotatable upon the bush 16. For the purpose of rotating this toothed segment 23 a shaft 24 is rotatably mounted in bearing blocks 25 on the side 55

wall of the press pedestal 1, and upon this shaft 24 is secured at the rear end a second toothed segment 26 meshing with the toothed segment 23, and at the front end a hand lever 27. By rocking the latter to and fro the worm 18 is rotated and the toggle-lever bearing 12 thereby displaced, as a result of which the position of the printing platen 3 in relation to the printing bed is changed.

On the front edge of the table 14 is secured a bearing block 28, in which is rotatably arranged a screw spindle 29 with a fine screw thread, which can be rotated by means of the knurled knob 30. Along the spindle 29 can be screwed a locking piece 31, constructed as a nut, which can be adjusted in relation to a scale 32 secured on the bearing block 28. The hand lever 27 has an upper portion 27¹, which is pivotally connected with the lower portion 27 by a bolt or pin 33 and is provided with a handle 27². A bolt 34 arranged in the portion 27¹ of the lever engages in a groove 35 in the locking piece 31 and thereby secures the position of the lever 27 and therefore of the toggle-lever bearing 12, and thereby also secures the position of the platen 3 in relation to the printing surface. The part 27¹ with the bolt 34 is held in engaging position by a spring not shown. By rotating the knob 30 the position of the platen, and therefore, the printing pressure, can be regulated while the machine is running. A fine adjustment of the pressure is therefore possible during operation.

If the handle 27² is tilted forwards so as to pull the pin 34 out of the groove 35, the lever 27 can be rocked into the position I (Figure 3), as a result of which the toggle-lever bearing 12, in the position of the parts indicated in Figure 2, is displaced to the right. The platen 3 then no longer touches the printing bed in its swinging movement, so the printing is stopped.

During the actual printing operation the pressure acting upon the toggle lever 9, 10 is propagated through the sliding pin 15 and the shearing ring 19 to the screw 18, which cannot over-haul, so that the parts controlling this screw are not in any way stressed, and the adjusting of the pressure, even in the case of large presses, can be effected without difficulty while the press is working.

If, during the printing operation excessive pressures occur from any cause, a projection on the sliding pin 15 shears off the internal collar (shown in Figure 2) of the shearing ring 19, as a result of which the toggle-lever bearing 12 can yield to the right, so that the press can for the moment continue to run without risk of breakage, because the printing is stopped. After taking out the screw 18 a fresh shearing ring 19 can be inserted.

What I claim is:—

1. An apparatus for adjusting and stopping the printing in automatic platen printing presses having a toggle mechanism for actuating the platen, comprising, in combination with an oscillable platen carrier, a toggle lever attached at one end thereto, a bolt connected with the opposite end of the toggle lever and extending in the direction of the same; a worm connected with said bolt, a stationary, internally threaded sleeve engaged by said worm; an arm connected with the worm at the free face thereof, a projection extending forth from said arm in the direction to the toggle lever; a toothed sector supported on the stationary sleeve and having a recess engaged by said projection, and means for turning said sector.

2. An apparatus for adjusting and stopping the printing in automatic platen printing presses having a toggle mechanism for actuating the platen, comprising, in combination with an oscillable platen carrier, a toggle lever attached at one end thereto, a bolt connected with the opposite end of the toggle lever and extending in the direction of the same; a worm connected with said bolt, a stationary, internally threaded sleeve engaged by said worm; an arm connected with the worm at the free face thereof, a projection extending forth from said arm in the direction to the toggle lever; a toothed sector supported on the stationary sleeve and having a recess engaged by said projection, another sector 15 meshing with the first-mentioned sector, and a lever connected with said other sector and situated at the front side of the machine.

3. An apparatus for adjusting and stopping the printing in automatic platen printing presses 20 having a toggle mechanism for actuating the platen, comprising, in combination with an oscillable platen carrier, a toggle lever attached at one end thereto, a bolt connected with the opposite end of the toggle lever and extending in 25 the direction of the same; a worm connected with said bolt, a stationary, internally threaded sleeve engaged by said worm; an arm connected with the worm at the free face thereof, a projection extending forth from said arm in the 30 direction to the toggle lever; a toothed sector supported on the stationary sleeve and having a recess engaged by said projection, another sector 35 meshing with the first-mentioned sector; a lever connected with said other sector and situated at the front side of the machine; a threaded spindle supported in the frame of the machine near the handle end of said lever; means for turning said spindle; a nut located on the spindle and having a lateral recess, and a member 40 extending forth from lever handle end into said recess.

4. An apparatus for adjusting and stopping the printing in automatic platen printing presses having a toggle mechanism for actuating the 45 platen, comprising, in combination with an oscillable platen carrier, a toggle lever attached at one end thereto, a bolt connected with the opposite end of the toggle lever and extending in the direction of the same; a worm connected with 50 said bolt, a stationary, internally threaded sleeve engaged by said worm; an arm connected with the worm at the free face thereof, a projection extending forth from said arm in the direction to the toggle lever; a toothed sector supported on the stationary sleeve and having a recess engaged by said projection, another sector meshing with 55 the first-said sector; a lever connected with said other sector, said lever comprising a body portion and a handle portion which is turnable at 60 said body portion at right angles to the direction of motion of the same; a threaded spindle supported in the frame of the machine near the handle end of said lever; means for turning said spindle; a nut located on the spindle and having a lateral recess, and a member extending forth from said lever handle portion into said recess.

5. An apparatus for adjusting and stopping the printing in automatic platen printing presses 70 having a toggle mechanism for actuating the platen, comprising, in combination with an oscillable platen carrier, a toggle lever attached at one end thereto, a bolt connected with the opposite end of the toggle lever and extending 75

in the direction of the same; a worm connected with said bolt, a stationary, internally threaded sleeve engaged by said worm; an arm connected with the worm at the free face thereof, a projection extending forth from said arm in the direction to the toggle lever; a toothed sector supported on the stationary sleeve and having a recess engaged by said projection, another sector meshing with the first-mentioned sector; a lever connected with said other sector, said lever comprising a body portion and a handle portion which is turnable at said body portion at right angles to the direction of motion of the same; a threaded spindle supported in the frame of the machine near the handle end of said lever; means for turning said spindle; a nut located on the spindle and having a lateral recess, a graduated scale extending along the path of the

nut, and a member extending forth from lever handle end into said recess.

6. An apparatus for adjusting and stopping the printing in automatic platen printing presses, comprising in combination a machine frame, a platen carrier oscillable in said frame, a toggle lever attached at the lower end of said platen carrier, a horizontally shiftable bolt connected with the opposite end of the toggle lever and extending in the direction of the same, a screw 10 threaded part turnably connected with said bolt, an internally threaded sleeve firmly fixed in said machine frame and engaged by said screw threaded part, means for turning said screw threaded part, and a handle in connection with said turning means and situated at the front side of the machine, and means for locking said handle in different positions.
